UNITED STATES PATENT OFFICE.

BRYSON D. HORTON, OF DETROIT, MICHIGAN.

ELECTRICAL SWITCH.

1,376,813.

Specification of Letters Patent.

Patented May 3, 1921.

Application filed January 22, 1915. Serial No. 3,703.

To all whom it may concern:

Be it known that I, BRYSON D. HORTON, a citizen of the United States, residing at Detroit, in the county of Wayne and State 5 of Michigan, have invented certain new and useful Improvements in Electrical Switches, of which the following, taken in connection with the accompanying sheet of drawings, is a full, clear, and concise description 10 thereof.

My present invention relates to certain improvements in that type of electrical switch commonly referred to as "iron" or "armor-clad" in which the switch mechanism is housed within a metallic protecting casing and is provided with means whereby it may be operated from without without requiring an opening of the cover and the exposure of the live conductor parts. The 15 object of my invention is to improve this general type of switch, to minimize the element of hazard, which is present in handling high potential currents, to improve and simplify the mechanical construction of 20 the switch mechanism itself and to improve the structural form of metallic or protecting housing.

Referring to the accompanying drawings:-

30 Figure 1 is a plan view of the switch mechanism embodying my invention, the cover of the casing being open to show more clearly the arrangement of the switch mechanism;

35 Fig. 2 is a view, partly in section, taken on line *a—a* of Fig. 1;

Fig. 3 is a horizontal sectional view taken on the line *b—b* of Fig. 1 with the cover in "closed" position and with the handle of 40 the switch in the extreme "off" position.

Fig. 4 is a detail in side elevation of the operating handle and oscillating spring-actuated mechanism which functions to cause an abrupt and quick break between 45 the contacts;

Fig. 5 is a perspective view of the connecting mechanism employed between the operating crank and the movable contact-actuator bar;

50 Fig. 6 is a perspective view of the connecting device between the actuator bar and the movable blade contact;

Fig. 7 is a similar view of a modified form of such connecting device;

55 Figs. 8, 9 and 10 are details of modified forms of contacts and fuse clip supports;

Fig. 11 is a plan view of a modified form of switch mechanism in which the accelerating mechanism is located between the actuator member and the operating crank; 60

Fig. 12 is a vertical cross-sectional view of the modification shown in Fig. 11 with the switch mechanism in its normal "on" position;

Fig. 13 is a like view of the modification 65 shown in Fig. 11 showing the accelerating spring expanded to a point where the connection between the contacts is about to be broken;

Figs. 14 and 15 are the perspective views 70 of modified forms of accelerating spring housings and connecting links between the actuator member and the operating crank;

Fig. 16 is a view in plan of a modified form of combined handle and accelerating 75 mechanism;

Fig. 17 is a view in side elevation thereof.

The stationary and coöperating movable contacts are mounted upon the base 1 of insulating material, which is fastened by any 80 suitable anchoring means 2, to the base of the metallic housing 3, the housing being provided with a hinged lid or cover 4. The stationary contacts are of the jaw type and are indicated by the numeral 5. These jaw 85 contacts are provided with fuse clips 6, which may be of an integral construction, *i. e.*, they may be formed of a single stamping of sheet metal bent into form as shown specifically in Fig. 8. Other and coöperating 90 fuse clips are employed to accommodate the opposite ends of the fuses. These latter fuse clips are provided with wire-receiving sleeves 8, which may be formed integral with the fuse clips 7, thus constituting a unit 95 construction made from a single sheet metal stamping, as shown specifically in Fig. 9. Coöperating with the jaw contacts 5 are the knife-blades 9, the latter being pivotally mounted at 10 to a jaw-like support 11. The 100 support 11 is provided with a wire-receiving sleeve 12, which may be formed integral with the support 11, making a one-piece sheet metal construction, as shown specifically in Fig. 10. The movably-mounted 105 blade contacts 9 are operated by a cross-bar or actuator member 13, this actuator member being either formed of insulating material throughout, or may comprise a metal bar 13 enveloped by insulating sleeves 13^a 110 (as shown in Fig. 12). I find it advantageous to use a metal cross bar 13 to con-

nect the movable contacts with the operating crank and suitably insulate said bar from the knife blade contacts such as by using fibrous or rubber sleeves 13^a, for the reason that the metal cross bar always maintains the knife blade in parallelism and in true alinement with the coöperating stationary jaw contacts. Experience has shown that where cross bars of fibrous or rubber or other non-metallic substances are used, that they will frequently warp and bend, making it impossible to keep the contacts in line with each other so as to effectively coöperate. It will be noted that when the insulating sleeves are clamped upon the cross bar 13 by means of the members 14, such sleeves will definitely anchor or position the connecting member or link. This actuator bar is connected to the knife-blade contact 9, through the instrumentality of the connecting device 14, as shown more clearly in detail in Fig. 6. This connecting device preferably is made from a single sheet of metal formed with a portion 15, conforming to the general contour of the actuator member 13, thus providing a seat therefor, and a depending part 16 to which the knife-blade contact is riveted by suitable rivets 17. In order to form a positive connection with the actuator bar, a screw bolt 18 is employed. This connector may take the form of a two-piece device, such as is illustrated in Fig. 7, the part 16 being separate from the part 14, but joined together by a screw 19, which also serves the purpose of tightening the enveloping part of the connector to the actuator bar. In order to prevent lateral displacement of the two parts, the lower free end of the part 14 is bent downwardly at 20 to form a rectangular abutment. This makes it obvious that in tightening the screw 19, rotary play or movement of the parts will be prevented as they are being drawn together. In order to provide for the actuation of the movable contacts, I provide a crank 21, which is mounted in the sides of the casing substantially at a point in line with the pivotal mounting of the pivoted blade contacts, thus providing for a substantial throw or swing of the movable contacts within a given limited space. The crank 21 is connected with the cross bar or actuator member 13 through the instrumentality of a two piece connecting member 22, which comprises two sheet metal parts provided with jaw or cut-out portions at 23 oppositely disposed one to the other so as to confine the actuator bar within the parts. The parts are held together by a bolt 24. Both parts are provided with apertures 25, which are threaded upon the crank before the same is bent into form. One end of the crank 21 is prevented from being sprung out of its bearing by the washer 26 and cotter pin 27. The

opposite bearing end of the crank shaft is mounted within two cup-shaped bearing members 28, riveted to the inner and outer sides of the casing. In order to provide for the throw of the crank to manipulate the switch mechanism, an exterior handle 29 is used. This handle is of one piece construction made from a piece of tubing slotted at 30 and swaged into an intermediate flat portion 31 and provided with curved end portions 32, the latter taking the conformation of the operating crank, and surrounding and having a bearing thereon. A bolt 33 serves to hold the parts together, but not sufficiently tight to prevent the handle from oscillating upon its bearing, to a limited extent, to provide for the proper manipulation of the switch.

By supporting the operating crank at both ends, or at both sides of the housing, it will be seen that substantial rigidity of construction is secured, although the parts themselves may not be carefully fitted or be of particularly substantial construction. Preferably also the operating crank is connected to the actuator bar in such a way as to exert a substantially balanced pull thereon, as in this way twisting strains upon the switch mechanism are avoided, the proper alinement of the knife-contacts with the jaw contacts is maintained, and the simultaneous breaking of both sides of the circuit is insured. In the particular example of my invention illustrated, this balanced pull is obtained by connecting the link 22 with the actuator bar substantially midway between the knife-blades, although it will be understood that other arrangements securing similar results may be employed.

These features, and also the making of the operating crank of an integral bent metal bar, are of great practical importance in the art as they contribute to the production of a switch which is strong, substantial, durable and reliable in operation, and which, at the same time, may be constructed at such a small cost as to make it available for every use. This is possible because the features of construction and organization referred to assure satisfactory operation without requiring the use of accurately fitted and machined parts which would make the cost of the switch prohibitive for most purposes.

In Figs. 16 and 17 are illustrated a modified form of operating handle which is also made of one piece, but of channel formation, the same being bowed, bent or reversed upon itself at 29^a, the free ends being brought together into rectangular formation at 29^b. The semicircular cut-out portions are provided for the accommodation of the operating crank 36.

In order to provide for a quick and rapid

break between the contacts, as is desirable in order to minimize sparking, I provide an accelerating mechanism to which the power of a spring is utilized to exert a force upon the crank to aid in its movement, thus making more rapid the "break" between the contacts. This feature of the invention comprises a curved rod 34, which is riveted and held fast to the operating handle 29 at 35. 10 This rod is mounted to reciprocate through an aperture 60 within the end of the bent-up portion 36 of the operating crank. Surrounding the rod 34 and held between the end of the bent-up portion 36 and a washer 15 37, is a spring 38, which is compressed when the handle 29 is operated to break the connection between the contacts as will be more fully explained.

In connection with the construction 20 shown in Figs. 16 and 17 the tension of the operating crank 36 and the accelerating mechanism are of the same general character as that heretofore described in connection with Figs. 1 to 4 inclusive.

25 In Figs. 11 to 13 inclusive I have illustrated a modified form in which the accelerating spring is mounted in the interior of the casing and preferably within a suitable housing at 30^a, which is carried by the operating crank 21 at one end and in sliding engagement with the actuator member 13 at its opposite end, said housing being suitably slotted at 30^b to permit of the required lost motion to bring the accelerating spring 30 into operation. The accelerating spring 38^a in this form is directly connected at one end 31^b to the operating crank, and at the opposite end at 31^c to the actuator member. The housing or connecting link 30^a is made 40 from a single piece of sheet metal bent and formed into the shape shown, the free ends being bolted around the crank 21 and fastened together by a suitable screw 32^a.

In Fig. 14 I have shown a modified form 45 of combined housing or connecting link. This is formed of a single piece of metal in channel formation, the two sides being slotted at 30^b for the accommodation and movement of the actuator member 13 and projecting hook-like ears 32^b. These ears project in diametrically opposite directions, thus forming the space 32^c for the accommodation of the operating crank 21.

In Fig. 15 the combined connecting link 55 and accelerating spring housing is made of two parts and, in some respects, is similar to that shown in Fig. 14 excepting that the ears 32^b project from the sides of the channel part in a common direction. A plate 33^a 60 is detachably connected to the channel part so as to afford retaining means for the operating crank when the same occupies the space 32^c. The plate 33^a is provided with apertures for the reception of the ends 33^b 65 of the ears 32^b and other apertures for the

accommodation of perforated ears 33^c, which are formed integral with the sides of the channel part and project therefrom.

In order to hold the channel part and the plate 33^a in operative position, a cotter pin 34^a is used, the same being inserted through the perforated ears 33^c, as shown.

In connection with the construction illustrated in Figs. 1 to 4 inclusive and 16 and 17, the operation of the mechanism may 75 be suitably described as follows:

Assuming the contacts to be in their closed position closely fitting one another, it will be obvious that inasmuch as the curved rod 34 moves with the handle 29 80 (and the latter being free to rotate on the bearing end of the crank 21) the crank 21 will not begin to move until the confined spring 38 is compressed between the washer 37 and the curved end 36 of the crank 21 85 sufficiently to overcome the adherence or frictional grip between the contacts. As soon as this is accomplished the spring expends its stored power and exerts it against the operating crank 21, causing it to swing 90 abruptly to break connection between the contacts.

The operation of the construction shown in Figs. 11 to 13 inclusive is somewhat analogous to the one heretofore described in 95 connection with Figs. 1 to 4 inclusive and 16 and 17. It will be obvious that since the connection between the operating crank 21 and the actuator member is through the accelerating spring 38, and since the actuator 100 member 13 is free to move within the connecting link or housing 30^a to a limited extent, the accelerating spring 38 is put under an expansive tension preliminary to the break between the contacts. By operating 105 the handle 29 the crank may be moved to the position shown in Fig. 13, at which time the contractile spring has been expanded and energy stored therein, which expends itself in the acceleration of the movable knife 110 blade contacts, thus causing a quick break and consequently minimizing the tendency toward arcing. If the frictional adherence between the jaw and knife-blade contacts is too great to be overcome by the power of the 115 contractile spring 38^a, the end of the connecting link or housing 30^a will engage the actuator member 13 and move it and the knife-blade contacts to a point where the spring tension is sufficient to effect a rapid 120 and complete break between the contacts.

The cover is provided with an enlargement 39 for the accommodation of the movable blade contacts and crank when thrown to their "off" positions.

In order to stop and lock off the switch mechanism in its inactive or "off" position, I provide mechanism which I will now describe. A plate 40 riveted to the under-side of the cover has a depending angular 130

extension 41. One end 41^a of this depending extension is adapted, in normal operation of the switch, to engage the crank 21 when the switch is in "open" position and 5 to thereby act as stop for the switch mechanism. The switch mechanism may be opened and closed as desired without any interference by this end of the extension. The extension is also provided with a notch 10 42 of sufficient size to accommodate the crank 21, so that after the cover has been opened and the crank moved to the extreme end of its contact breaking position, and the cover thereafter closed, the crank may be 15 seated within the notch 42 and be prevented from moving toward its contact closing position. The contour of this notch and its location relative to the pivot of the crank and hinge of the casing is such, that when one 20 moves the crank away from the extreme "off" position at the left, as shown in Fig. 3, toward the "on" position, the crank will be intercepted and extension 41' will engage the crank on the side thereof, facing the pivot, 25 so that the cover cannot be opened by forcing the crank toward "on" position.

I also provide, as shown in Figs. 1 and 3 a stop 40' fast to a side of the casing and in a 30 position to intercept the crank when moved toward the extreme "open" position after the cover has been opened. By thus limiting the movement of the crank it is impossible to crowd the crank over against the leads, when the cover is open, thereby possibly 35 short circuiting the line. It is also especially desirable to so limit the crank movement in switches wherein the fuses are on the side of the switches next the knife blades. Further this stop 40' coöperates with the extension 40 41, when the switch is locked "off," to restrict the crank to a limited movement only.

It will, therefore, be apparent that the plate 40 with its depending extension 41 is 45 adapted to function both for arresting the movement of the switch in normal operation at a predetermined point, when the switch crank 21 engages the end 41^a of this extension, and it is also adapted to lock the switch mechanism at another point, namely, the extreme "off" position whenever it is desired 50 to lock the switch "open" on account of the notch 42 engaging the switch crank 21. When the switch is locked completely "off," the switch crank lies between the top of the 55 plate 40' and the notched part 42 of the extension 41.

In order to provide for the convenient wiring of the switch, the ends of the casing are apertured at 43 and 44. The apertured 60 end 43 is normally closed by a plate 45, provided with knock-out portions 46, which may be of the desired number to conform to the number of wires that are employed. This plate is held in place by lugs 47, and is 65 confined within the casing by the cover

thereof, when in closed position. The plate, it will be understood, may be withdrawn from the casing when it is desired to knock out the knock-out parts 46, preparatory to wiring the switch. The opposite apertured 70 end of the casing is likewise provided with detachable or removable end plates of like mounting, excepting that the plate itself is provided with an oblong slot in which is mounted a porcelain insulating bushing 48, 75 provided with suitable holes 49 conforming in size to the particular wires that are employed.

I do not wish to be understood as limiting myself to the precise structure shown and 80 described as the same may be varied and departed from and still be within the spirit and scope of my invention as set forth in the appended claims.

Having thus described my invention, what 85 I claim as new herein and desire to secure by Letters Patent, is:—

1. In combination with a metal housing, of a base, a plurality of stationary contacts mounted on said base, a plurality of knife 90 blade contacts pivotally mounted at one end to said base and adapted to coöperate at their other ends with said stationary contacts, a cross arm secured to said knife blade contacts at a distance removed from the free 95 ends of said blade contacts, a crank mounted to swing about an axis in alinement with the axis of said knife blade contacts, said crank having an elongated portion parallel with said cross arm, and lateral arms shorter than 100 said knife blade contacts, an elongated link connecting the elongated portion of said crank with the middle of said cross arm, a handle secured to said crank and disposed exteriorly of said metallic housing for operating said crank, a cover for said metallic housing, and an obstruction on said cover engaging said crank when the switch is in "off" position and the cover has been closed thereby locking the switch in such "off" 105 position.

2. In an armor clad switch, in combination, a metallic housing comprising a cover, sides and a hinge between said cover and one side, and a switch mechanism including a 115 crank journaled in one of the sides of the housing, said cover carrying a depending extension projecting into the housing and having a notch therein, a wall of said notch being disposed, when the cover is closed and 120 the crank is in the "off" position, in the path of the crank to intercept it when moved toward the "on" position, a portion of said extension comprising means to engage the crank, when so intercepted, and prevent the opening of the cover by the crank, substantially as described.

3. In an electrical switch, the combination of a housing, a base of insulating material therein, a plurality of spaced stationary con- 130

- tacts on said base, a plurality of knife blade contacts pivotally mounted at one end on said base, a transversely extending actuating member extending over said knife blade contacts and rigidly connected thereto, at a distance removed from their free ends, an operating crank mounted to swing about an axis in alinement with the axis of said knife blade contacts, and having a portion extending over and substantially parallel with said actuating member and lateral arms shorter than said knife blade contacts, an elongated link connecting said crank portion with said actuator member at an intermediate position on said member and an operating handle mounted exteriorly of the housing and operatively connected to said crank to manipulate the crank and said contacts.
- 5 4. In an armor-clad switch, in combination, a metallic housing comprising a cover, sides and a hinge between said cover and one side, and a switch mechanism including a crank journaled in one of the sides of the housing, said cover carrying a depending extension in the path of the crank when the
- 10 cover is closed, to interengage with the crank when moved from the extreme "off" position toward the "on" position, said extension comprising means whereby when the cover is closed and the crank is so moved the crank and extension parts will interlock so that forcing of the cover open by the crank will be prevented substantially as described.
- 15 5. In an armor clad switch, the combination with a metallic housing comprising a movable cover and sides, and a switch mechanism including a crank journaled on one of the sides of the housing, of means on the cover, when closed, for locking the crank in the limiting position of its movement, and means on said housing and coöperating with the locking means on said cover to limit the oscillation of said crank when the switch is locked in off position.
- 20 In witness whereof I have hereunto set my hand in the presence of two subscribing witnesses.
